UNITED STATES PATENT OFFICE.

WILLIAM FRANCIS BARRY, OF LOS ANGELES, CALIFORNIA.

DESIGN FOR AN ADVERTISING CARD.

Application filed September 21, 1925. Serial No. 14,836. Term of patent 3½ years.

To all whom it may concern:

Be it known that I, WILLIAM FRANCIS BARRY, a citizen of the United States, residing at Los Angeles, in the county of Los Angeles and State of California, have invented a new, original, and ornamental Design for Advertising Cards, of which the following is a specification, reference being had to the accompanying drawing, forming part thereof.

The figure is a perspective view of an advertising card, showing my new design.

I claim:

The ornamental design for an advertising card, as shown.

In testimony whereof I affix my signature.

WILLIAM FRANCIS BARRY.
